UNITED STATES PATENT OFFICE.

GEORGE C. BROWN, JAMES M. McDONALD, AND GEORGE C. BRENNING, OF NEW ROCHELLE, NEW YORK, ASSIGNEES, BY MESNE ASSIGNMENTS, TO J. C. PENNEY COMPANY, A CORPORATION OF DELAWARE.

HAT.

Application filed March 31, 1924. Serial No. 703,124.

To all whom it may concern:

Be it known that we, GEORGE C. BROWN, JAMES M. McDONALD, and GEORGE C. BRENNING, citizens of the United States, and residents of New Rochelle, county of Westchester, State of New York, have invented certain new and useful Improvements in Hats; and we do hereby declare the following to be a full, clear, and exact description of the invention, such as will enable others skilled in the art to which it appertains to make and use the same.

This invention relates to men's hats; and more particularly to the type of hat known as a soft hat, which may be made of cloth, felt, or other similar material. Such hats are ordinarily worn with the crowns dented or creased and when the hat is removed and again placed on the head it frequently happens that the crease will be removed. It then becomes necessary for the wearer to give the crown the desired original shape, and this is frequently a source of annoyance, as well as, in time, giving the hat a worn appearance.

The object of the present invention is to provide a hat having means within the crown by which the crease ordinarily made in the crown may be retained at all times. This hat is provided with fastening members secured within the crown and concealed from outward view, and these fastening members may take the form of parts of snap fasteners. The hat is also provided with a retaining device in the form of a flexible strip which may be made of tape or other similar material and on each end of which are placed snap fastener parts which may be secured to those attached to the crown. The fastening devices secured to the crown are placed at a considerable distance to either side of the line along which the crease is usually made, and the tape is considerably shorter than the distance between these fasteners when the crown is uncreased. When the fastening devices on the tape are secured to those on the crown the crown is held in creased position and will retain this shape indefinitely the tape preventing the sides of the crown from bulging apart and thus opening up the crease. The strips may be provided in different lengths so that the sides of the crease may be tightly or loosely held together as may be desired. Also by

removing the tape from the hat the hat may be worn with the crown in its original shape without a crease.

In the accompanying drawings we have illustrated that embodiment of the invention which is now preferred, and in these drawings,

Fig. 1 is a view in perspective of a hat showing the retaining device in use therein,

Fig. 2 is a cross-sectional view showing the relation of the walls of the crown when the retaining device is in use,

Fig. 3 is a view of the hat showing the retaining device removed and the crown uncreased,

Fig. 4 is a cross-sectional view of a portion of the hat through the crease, showing the method of securing the retaining device to the crown, and

Figs. 5 and 6 are views of strips of different lengths.

Referring now to these drawings, the hat illustrated is of the type commonly known as the fedora, and may be made of cloth, soft felt, or other similar material. It has the usual brim 7, and crown 8, which, when distended, is somewhat oval in cross-section, and has a more or less flat top. Such hats are ordinarily worn with the crease indicated at 9, in Fig. 1, and, as shown in Fig. 2, the crown is folded inwardly as at 10 and the side walls of the crown are then dented in as at 11. Within the crown there is provided a lining 12 which is usually of light, thin silk, or other similar material. The crown is held in its creased position by means of the retaining device generally indicated at 13, and shown more clearly in Figs. 5 and 6.

This retaining device consists of a fabric strip 14 which may be made of one or more strips of tape. As shown in Fig. 4, the device consists of two strips of tape 15. At the ends of the strip, fastening devices 16 are provided which may conveniently take the form of the socket members of snap fasteners of a well-known type. These snap fasteners consist of a receiving member 17 and a head member 18. The receiving member passes through a hole in the strip and the head is clamped over the end thereof so that the strip is firmly held between the two members forming this part of the fastener. The stud members of the snap fas-

tener consist of two members 19 and 20 which are forced together in such a manner as to clamp a portion of the lining 21 between them so that the fastener is firmly secured to the lining. The fastening members thus secured to the lining are spaced apart a considerable distance on either side of the line along which the crease is usually made. Also they are concealed from outward view but as the lining is securely held to the material forming the crown, the crown will be retained in its creased shape when the retaining device is in place.

In cloth hats it is customary to provide a lining which is stitched to the hat with a plurality of rows of stitching, and this lining may be made up of several portions, one of which has the oval shape indicated at 22. A reinforcing strip 23 is then stitched in place so as to unite the several parts of the lining and give it a finished appearance. This reinforcing strip has portions which lie to either side of the crease and may well be used as the means by which the fastening devices are secured to the crown.

This construction has been illustrated in Fig. 4, in which the reinforcing strip is shown gripped between the two parts which form the stud member of the fastening device. The strip is then united to the lining and also the crown, by rows of stitching indicated at 24, the other rows of stitching by which the lining is secured to the crown not being illustrated.

When the device is to be put in place, the crown is first creased so as to assume the desired shape, and then a retaining device having a tape of the length which depends on the shape in which the hat is to be held, is attached by means of the fastening devices in the position illustrated in Fig. 2. With the retaining device in position the creased shape given the crown is always maintained, regardless of the force that is exerted upon

the crown when the hat is removed and replaced. The hat consequently retains the desired appearance, even after long continued wear. At the same time since the fastening device is concealed from view, the outward appearance of the hat is not changed. The fastening device does not add to the weight of the hat, and since it does not come in contact with the head of the wearer, it occasions no discomfort.

We claim:

1. A soft hat having a crease in the crown thereof, fastening devices disposed on the inside of the crown at either side of the crease, and a flexible strip separable from the hat and having fastening devices at either end adapted to engage with the fastening devices first mentioned.

2. A soft hat having a crease in the crown, a lining in the crown, fastening devices secured to the lining on either side of the crease, and a flexible strip separable from the hat and having fastening devices at either end adapted to engage with the fastening devices first mentioned.

3. A soft hat having a crease in the crown, a lining in the crown having a reinforcing band extending around the top of the crown, with portions lying on either side of the crease, fastening devices secured to the said portions of the band, and a flexible strip separable from the hat and having fastening devices at each end adapted to engage with the fastening devices first mentioned, this strip having a length less than the distance between the fastening devices on the crown when the crease is removed from the latter.

In testimony whereof we affix our signatures.

GEO. C. BROWN.
JAMES M. McDONALD.
GEORGE C. BRENNING.
